UNITED STATES PATENT OFFICE.

LEOPOLD BAKKE, OF CHICAGO, ILLINOIS.

PRINTING-PRESS.

1,096,590.

Specification of Letters Patent. Patented May 12, 1914.

Application filed February 19, 1914. Serial No. 819,665.

To all whom it may concern:

Be it known that I, LEOPOLD BAKKE, a citizen of the United States, and a resident of Chicago, in the county of Cook and State 5 of Illinois, have invented certain new and useful Improvements in Printing-Presses, of which the following is a full, clear, and exact specification.

My invention is concerned with improvements in printing presses of the Gordon type, shown in my application No. 798,630, filed November 1, 1913, and allowed January 31, 1914, the patent for which I expect to have issued simultaneously herewith, 10 and in which yielding link connections between the swinging type-bed frame and the swinging platen are substituted for the customary cam connections ordinarily used for swinging the latter. In my aforesaid application No. 798,630, the press is not provided with a "throw-off," and in my present application, I show the same invention as applied to such a Gordon press having a throw-off, the presence of which in the press necessitates the modification of the structure 15 shown in my aforesaid application in the manner hereinafter described.

To illustrate my invention, I annex hereto two sheets of drawings, in which the same 20 reference characters are used to designate identical parts in all the figures, of which—

Figure 1 is a perspective view of the rear of a press embodying my invention, this 25 particular view being designed more especially to illustrate the throw-off connections; Fig. 2 is a side elevation seen from the side on which the yielding link is located; Fig. 3 is a detail section showing part of the train of connections leading from the throw-off lever to the eccentric shaft, the rocking 30 of which operates the "throw-off;" Fig. 4 is a longitudinal vertical section through the yielding link; Fig. 5 is a detail in horizontal section on an enlarged scale, on the line 45 A—A of Fig. 2; and Fig. 6 is a detail in section on the line B—B of Fig. 5.

The customary type of Gordon press employs the stationary main-frame 10, in which is mounted the drive shaft 11, rotated 50 by any suitable source of power, as by means of belts associated with the belt-wheels 11^a mounted on said shaft 11 in the customary manner. This shaft 11 carries a spur-gear pinion 12 meshing with a spur-gear wheel 55 13 secured on a shaft 14, also journaled in the frame 10. An eccentric pin 15 on the

spur-gear wheel has pivoted thereon a link 16, which is pivotally connected to the reduced bearing end 17 of the eccentric shaft 18 journaled in the bed-plate frame 19, which has arms 20 extending down toward the bottom of the frame and pivotally mounted thereon on a shaft 21. It will be understood that the crank pin 15, link 16, reduced bearing end 17, and the arm 20, are 60 duplicated on the other side of the machine to give it symmetry and properly support the parts. The bed-plate frame 19 carries the customary type-bed at 22, and it will be obvious that the rotation of the shaft 14 65 tends to bring the bed-plate first to printing position, and then to retract the same for the inking operation, which is effected by the customary inking rollers carried in the customary swinging inking-frame, the side 70 pieces of which I have numbered 23, and which slide back and forth on the eccentric shaft 18 in the customary manner.

Journalized in the frame 10 is a rock shaft 24, which has secured thereon the platen 25, 80 which is swung up to the position shown in full lines in Fig. 2, where it is adapted to have the paper to be printed placed thereon by hand during the time that the bed plate is retracted for inking the type. When an 85 impression is taken, it is obvious that the rock shaft 24 must be rocked to the dotted-line position, and the frame 19 similarly 90 swung to its dotted-line position to make an impression, and my present invention is concerned with the connections by which the movement of the rock shaft 24 is effected in the proper synchronisms to swing the platen back and forth at the proper times and with the proper interval between its movements. 95

In carrying out my invention, I secure on the rock shaft 24 an arm 26, and connect this arm to the bed-plate frame by a link, which I will designate generally by the numeral 27. The details of construction of 100 this link are best shown in Figs. 2 and 4, where it will be seen that the inner end is formed preferably of a tube 28, in which is placed a helically-coiled expanding spring 29, which tends to hold the reduced end 30 105 of the outer portion 31 in the position shown in Figs. 2 and 4, in which position the pin 32 secured in the tube 28, and passed through a slot 33 in said reduced end 30, is in its outermost position in said slot. The outer portion 31 is also provided with a helically-coiled expanding spring 34 mounted therein 110

and adapted to have its tension increased or diminished by a set screw 35 threaded through a nut 36 secured in the outer end of the portion 31, and coöperating with a 5 plug 37, against which the end of the spring 34 rests. The inner end of the portion 31 preferably takes the shape of an open guide-slot 38, in which a block 39 is adapted to reciprocate, said block being preferably provided with a pin 40 extending into the end 10 of the coil of the spring 34. The block 39 is held by a pivot pin 41 in its position on the inner side of a lever 42 pivoted at its lower end on the shaft 21, and secured at its 15 upper end in the manner to be hereinafter described.

In the structure shown in my aforesaid application, No. 798,630, the pin 41 is secured on a bracket extending from the side 20 of the frame 19, to which it is rigidly connected. Assuming, for the purposes of the preliminary description, that the lever 42, to which the pin 41 is connected, is rigid with the bed-plate frame 19, the operation of the 25 novel movement, as shown in my aforesaid application and in the present application, is as follows: Assuming that the parts are in the position in which the bed-plate frame 19 is retracted as far as possible from the 30 platen,—in this position, the block 39 occupies the outer portion of the guide-slot 38, and the spring 34 is compressed. As a result of the operation of this spring, when the bed-plate frame 19 begins to swing from 35 its outermost position toward the platen, the link 27 is held from movement until the bed-plate frame 19 has swung inward far enough so that the block 39 can move to the inner end of the slot 38 under the pressure of the 40 spring 34. This holding the link 27 from movement for this interval increases the length of time in which the platen is held in the feeding position, so that the operator has that much more time to place the paper 45 carefully on the platen. At the end of this movement of the block 39 in the slot 38, the further inward movement of the bed-plate frame 19 moves the link 27 inward, and as it moves, it rocks the shaft 24, bringing it 50 ultimately down to the printing position, and when it reaches this position, the spring 29 is still expanded, with the pin 32 at the outer end of the slot 33. The taking of the 55 impression necessitates a further inward movement of the bed-plate frame, and as the crank arm 26 and the portion 28 of the link cannot move any farther, the outer portion 31 of the link 16 continues its movement by reason of the reduced end 30 passing 60 farther into the portion 28, compressing the spring 29 as much as may be necessary to secure the desired sharpness of impression. At the end of this inward movement, the link 16, of course, begins to move outward, 65 and this carries the bed-plate frame 19 out-

ward. When this outward movement starts, the spring 29 expands until the pin 32 rests in the outer end of the slot 33, after which the link 27 moves as a whole, and the shaft 24 is rocked to swing the platen 25 to the 70 proper receiving position. Toward the end of the outward movement of the bed-plate frame 19, the platen 25 is brought to paper-receiving position, in which it cannot be swung any farther, after which the continued movement of the bed-plate frame 19 75 is permitted by reason of the block 39 moving outward in the slot 38 and compressing the spring 34, as previously mentioned.

The description of the press and its construction so far would be applicable to the press shown in my application No. 798,630, which is not provided with a "throw-off", except that, as previously stated, the pin 41 is secured on a bracket rigidly secured on 80 the side of the bed-plate frame 19, and the shaft 18 need not be an eccentric shaft. Where the "throw-off" is employed, the shaft 18 is rocked in its bearings by mechanism to be described, and as a result of the 85 rocking of said shaft in the proper direction to put the throw-off in action, the reduced end 17 has no motion of translation in its bearing in the end of the link 16, and, as a consequence, the upper portion of the bed-plate frame 19 is swung back a distance that 90 would be determined by the eccentricity of the shaft 18 and the angle through which it is swung. When it is thus swung back, as the press continues to operate, the type are 95 not brought into engagement with the platen as the parts approach each other. The rocking of this shaft 18 may be effected in various ways, and I have shown the customary construction, in which the throw-off hand-lever 43 is pivoted to a bracket 44 secured on the frame 10, and has a link 45 secured at its lower end, connected to an arm 46 on a rock shaft 47, which is journaled in the frame 10. This rock shaft 47 carries the 100 "throw-off pin-circle" lever 48, which has a pin 49 engaging a slot 50 in the arm 51 of a lever 52, secured on a rock shaft 53, the other arm 54 of which lever is connected by a link 55 with an arm 56 of the "throw-off 105 saddle" 57 secured on the eccentric shaft 18. With the connections thus shown, as the lever 43 is swung forward or back, the eccentric shaft 18 will be rocked to operate the throw-off in the customary manner. If the 110 pin 41 is connected to a part rigid with the bed-plate frame 19, as in the structure shown in my aforesaid application No. 798,630, the press will operate all right while the throw-off is not in operation, but when the throw-off lever has been shifted to throw the bed-plate frame 19 back far enough so that the type-bed will not engage the platen at the 115 end of the impression swing, the tendency is to rock the platen 25 too far, and thus tend 120 to rock the platen 25 too far, and thus tend 125 to rock the platen 25 too far, and thus tend 130

to rack the machine and make a noisy operation. To overcome this difficulty, I have secured the pin 41, as before described, on the inner face of the lever 42, and the upper end 5 of said lever 42 is pivotally connected to an eccentric strap 58, which preferably has anti-friction rollers 59 interposed between the strap 58 and a disk 60, which is mounted eccentrically on the end of the eccentric 10 shaft 18, but which is concentric with the reduced bearing end 17 of said shaft. Consequently the lever 42 does not swing with the bed-plate frame 19 when the throw-off mechanism is operated, and therefore the 15 link 27 moves the platen 25 only the proper distance, whether the throw-off mechanism is or is not in operation.

While I have shown and described my invention as embodied in the form which I 20 at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In a press, the combination with a frame, of a driving shaft journaled therein, 30 a swinging bed-plate pivoted on the frame, a platen pivoted on the frame, connections between the shaft and bed-plate for swinging the latter to and from the platen, once for each rotation of the shaft, throw-off 35 mechanism for varying the position of the bed-plate relative to the frame, a crank-arm connected to the platen, a yielding link connecting the crank-arm and the bed-plate, means for preventing the movement of the 40 crank-arm during the inward portion of the movement of the bed-plate until the latter reaches a certain position, and a member moving with the bed-plate to which the link is connected, said member being unaffected 45 by the operation of the throw-off mechanism.

2. In a press, the combination with a frame, of a driving shaft journaled therein, 50 a swinging bed-plate pivoted on the frame, a platen pivoted on the frame, connections between the shaft and bed-plate for swinging the latter to and from the platen, once for each rotation of the shaft, throw-off 55 mechanism for varying the position of the bed-plate relative to the frame, a crank-arm connected to the platen, a yielding link connecting the crank-arm and the bed-plate, means for preventing the movement of the 60 crank-arm during the inward portion of the movement of the bed-plate until the latter reaches a certain position, said means consisting of a spring that is compressed during the final portion of the outward movement of the bed-plate, and whose expansion 65 during the first portion of its inward move-

ment prevents the movement of the link until the spring has expanded, and a member moving with the bed-plate to which the link is connected, said member being unaffected by the operation of the throw-off 70 mechanism.

3. In a press, the combination with a frame, of a driving shaft journaled therein, a swinging bed-plate pivoted on the frame, a platen pivoted on the frame, connections 75 between the shaft and the bed-plate for swinging the latter toward and from the platen, once for each rotation of the shaft, a crank-arm connected to the platen, a yielding link connecting the crank-arm and bed-plate, and including two springs, one of 80 which is compressed during the final portion of the outward movement of the bed-plate, and whose expansion during the first portion of the inward movement prevents 85 the movement of the link until said spring has expanded, and the other one of which is compressed effectively to shorten the link at the time the impression is actually taken, throw-off mechanism for varying the position 90 of the bed-plate relative to the frame, and a member moving with the bed-plate to which the link is connected, said member being unaffected by the operation of the 95 throw-off mechanism.

4. In a press, the combination with a frame, of a driving shaft journaled therein, a swinging bed-plate pivoted on the frame, a platen pivoted on the frame, connections 100 between the shaft and the bed-plate for swinging the latter toward and from the platen, once for each rotation of the shaft, a crank-arm connected to the platen, a two-part link connecting the crank-arm and the bed-plate and having telescoping connections, a spring in said link tending to 105 keep it extended, throw-off mechanism for varying the position of the bed-plate relative to the frame, and a member moving with the bed-plate, to which the link is connected, said member being unaffected by the 110 operation of the throw-off mechanism.

5. In a press, the combination with a frame, of a driving shaft journaled therein, a swinging bed-plate pivoted on the frame, a platen pivoted on the frame, connections 115 between the shaft and the bed-plate for swinging the latter toward and from the platen, once for each rotation of the shaft, a crank-arm connected to the platen, a two-part link connecting the crank-arm and the bed-plate and having telescoping connections, a spring in said link tending to keep 120 it extended, a second spring carried by the link and compressed by the connection of the bed-plate with the link at the end of the outward movement of the bed-plate to increase the effective length of the link, throw-off mechanism for varying the position of 125 the bed-plate relative to the frame, and a 130

member moving with the bed-plate, to which the link is connected, said member being unaffected by the operation of the throw-off mechanism.

5. 6. In a press, the combination with a frame, of a driving shaft journaled therein, a swinging bed-plate pivoted on the frame, a platen pivoted on the frame, connections between the shaft and the bed-plate for 10 swinging the latter toward and from the platen, once for each rotation of the shaft, a crank-arm connected to the platen, a link connecting the crank-arm and the bed-plate, and comprising a tubular inner portion having 15 a helically-coiled expanding spring therein, and an outer portion having its inner end telescoping in the outer end of the inner portion, and having a recess therein adjacent its inner end, a helically-coiled expanding spring in said outer portion beyond the recess, a block sliding in a recess in said outer portion, throw-off mechanism for varying the position of the bed-plate relative to the frame, and a member 20 moving with the bed-plate, upon which the block is pivoted, said member being unaffected by the operation of the throw-off mechanism.

7. In a press, the combination with a main 30 frame, of a driving shaft journaled therein, crank-pins carried by said shaft, a swinging bed-plate pivoted on the frame, a platen pivoted on the frame, an eccentric shaft in the bed-plate, links connecting the ends of 35 the eccentric shaft and the crank-pins, throw-off mechanism for rocking the eccentric shaft to vary the position of the bed-plate relative to the frame, a crank-arm connected to the platen, a yielding link connected 40 at one end to the crank-arm, a lever having the same fulcrum as the bed-plate, the other end of the link being connected to said lever, and connections between said lever and the eccentric shaft, said connections being unaffected by the rocking of said eccentric shaft.

8. In a press, the combination with a main frame, of a driving shaft journaled therein,

crank-pins carried by said shaft, a swinging bed-plate pivoted on the frame, a platen pivoted on the frame, an eccentric shaft in the bed-plate, links connecting the ends of the eccentric shaft and the crank-pins, throw-off mechanism for rocking the eccentric shaft to vary the position of the bed-plate relative to the frame, a crank-arm connected to the platen, a yielding link connected to one end of the crank-arm, a lever having the same fulcrum as the bed-plate, the other end of the link being connected to 60 said lever, an eccentric strap pivotally connected to the upper end of said lever, and an eccentric disk in said eccentric strap secured on the eccentric shaft concentric with the bearings for the links connecting the eccentric shaft and the crank-pins.

9. In a press, the combination with a main frame, of a driving shaft journaled therein, crank-pins carried by said shaft, a swinging bed-plate pivoted on the frame, a platen pivoted on the frame, an eccentric shaft in the bed-plate, links connecting the ends of the eccentric shaft and the crank-pins, throw-off mechanism for rocking the eccentric shaft to vary the position of the bed-plate relative to the frame, a crank-arm connected to the platen, a yielding link connected at one end to the crank-arm, a lever having the same fulcrum as the bed-plate, the other end of the link being connected to 70 said lever, an eccentric strap pivotally connected to the upper end of said lever, an eccentric disk in said eccentric strap secured on the eccentric shaft concentric with the bearings for the links connecting the eccentric shaft and the crank-pins, and roller bearings interposed between said eccentric strap and its eccentric disk.

In witness whereof, I have hereunto set my hand and affixed my seal, this 12th day of February, A. D. 1914.

LEOPOLD BAKKE. [L.S.]
